CLAIM

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Enlarged

1.9 : Enlarged

The dash-dot broken lines of figures 1.1, 1.4, 1.8 and 1.9 are included to show partially enlarged views only and form no part of the claimed design.

1 Claim, 8 Drawing Sheets(56)
